UNITED STATES PATENT OFFICE

ALFRED D. LUEHRMANN AND FRANCIS X. MEEHAN, OF ST. LOUIS, MISSOURI
MEANS FOR REGULATING THE INTENSITY OF ACTION OF MASSAGING OR EXERCISING MACHINES

Application filed July 11, 1928. Serial No. 291,864.

This invention relates to certain new and useful improvements in exercising or massaging machines. There are various types of these machines, but they are all characterized by the fact that two arms are rapidly reciprocated in alternation and a belt having its ends secured to these arms is applied to the body and rapidly drawn back and forth to produce a massaging effect upon the part of the body to which it is applied.

While many of these machines have adjustable features for reducing or increasing the severity of the action of the belt, the adjustment of the machines is not always easy, especially for women, and cannot be effected while the machine is in use. Some makes of machines have no means for adjusting the degree of the agitating action whatever.

Many persons have had operations of one kind or another, leaving the particular part of the body where the operation was performed very sensitive, or some part of the body may be sensitive due to some abnormal condition, and a massaging action of these machines that would be pleasant and stimulating at one part of the body will be too severe, and even painful, when applied at such a sensitive part of the body. In such cases, the one using the machine must either be content with a gentle action for the whole body, or must interrupt the treatment and adjust the machine to accommodate its motion to some sensitive part of the body.

It is the object of our invention to enable the degree of the exercising or massaging action of the belt employed to be readily adjusted by very simple manipulations and in a very short time, and without the user of the machine having to remove the belt from his body.

With the above object in view, our invention consists in applying means to the belt for adjustably drawing the end portions of the belt, between the body of the user and the machine, toward each other, which we have discovered operates to very decidedly decrease the severity of the action of the belt.

A further object of the invention is to provide means for applying the adjusting device to the belt at different points in the end por-

tions thereof, whereby a great range of adjustment in the action of the belt is secured.

In the accompanying drawing—

Figure 1 is a side view of an exercising belt with an adjusting device mounted thereon;

Figure 2 is a plan view of the same;

Figure 3 is a cross-section on an enlarged scale taken on the line 3—3 of Fig. 1;

Figure 4 is a side view slightly in perspective illustrating the use of the invention; and

Figure 5 is a cross-sectional view similar to Fig. 3 illustrating a preferred form of adjusting device.

Referring now to the drawing, the numerals 1, 2 indicate, respectively, the hooks on the two arms of an exercising or massaging machine, on which hooks the ends of a belt 3 are adapted to be removably secured. To this end, each end of the belt is provided with a loop 4, usually of leather, which may be readily inserted over the hooks 1, 2. The belt 3 is usually of canvas. When so applied and with the hooks 1 and 2 vibrating rapidly in alternation, the belt will be drawn rapidly back and forth on the body of the user, producing a more or less violent agitation of the body, depending upon the degree of severity of the vibrating action employed. We will now describe the means which we employ for regulating the severity of the action of the exercising belt 3.

The numerals 5, 6, and 7 indicate, respectively, corresponding sets of eyeleted openings formed in the end portions of the belt 3 at corresponding distances from the ends thereof. That is to say, the corresponding apertures 5 are located at a comparatively short distance from the respective ends of the belt, the apertures 6 at a greater distance, and the apertures 7 at the greatest distance from the ends of the belt. Into one or the other sets of these apertures, we insert suitable means, to be operated by the user, for drawing the end portions of the belt toward each other. In one form of the invention, we may employ any flexible means for this purpose, such as a rope or a chain, which may be either simply pulled on by the user to draw the end portions of the belt toward each other,

and be held in any given adjusted position while the given part of the body is being massaged; we find it desirable, however, to hold the adjusting device in any position to 5 which it is adjusted, in order to leave the hands of the operator free, and we have accordingly illustrated a chain having a snap-hook on one end to be used for this purpose. Thus, as shown in Fig. 3, the chain 8 is passed 10 through the apertures 6 in the two end portions of the belt and in a manner to extend between such end portions as shown, and then the snap-hook 9 on one end of the chain is engaged in one of the links of the other end 15 portion of the chain. At any time, the user of the machine can readily decrease or increase the degree of vibration effective on the body by removing the snap-hook from one link and securing it in a link further away 20 or nearer to the other end of the chain, as the case may be. The nearer the end portions of the belt between the body of the user and the machine are brought together, the less severe the action of the belt on the 25 body. Therefore, by releasing the snap-hook and increasing the distance between the two end portions of the belt, the vibrating or agitating action of the belt can be increased in intensity. This range of adjustment, of 30 course, can be employed with each of the series of openings 5, 6 and 7. When the adjusting chain 8 is placed in the apertures 7, the degree of agitation for any adjustment is considerably less than applies when the 35 chain is positioned in the central set of apertures 6, and the same relative difference exists between the apertures 6 and the apertures 5 as respects the degree of agitation for a given adjustment.

40 In Fig. 5, we have shown a preferred form of adjusting device, which is the invention of Alfred D. Luehrmann, one of the co-inventors herein, and which forms the subject matter of a separate application for patent. This 45 device is made of metal and comprises two telescoping members which are adapted to be inserted in one or the other of the sets of apertures in the end portions of the belt and to be adjusted in various positions to draw 50 such end portions of the belt toward each other.

To this end, one member of the device is formed of a metal bar having the shape, substantially, of an elongated U providing a 55 head 10 and two legs 11, 12. The other member of the device is of substantially the same shape, having a head 13 and legs 14 and 15. The legs 14 and 15 of the second member of the device are hollow and are adapted to receive 60 the legs 11 and 12 of the first named member of the device. The upper leg 11 of this latter device is provided on its upper side with a series of ratchet teeth 16. The leg 14 of the second named member of the device 65 is somewhat shorter than the lower leg 15

and has on its inner end an upright tubular projection 17 in which is mounted a ratchet pin 18 normally pressed into engagement with the teeth 16 of the leg 11 by a coil spring 19. The upper end of the projection 17 is 70 screwthreaded and a cap 20 screwed on this outer end maintains the ratchet pin in proper position. The said ratchet pin projects through the upper end of this cap and has a head 21 by grasping which with the fingers, 75 the ratchet pin may be lifted out of engagement with the ratchet teeth to enable the two members of the adjusting device to be pulled apart and, if necessary, separated. This latter, of course, is necessary when first applying the device to the belt, in order to enable the respective legs of the two members of said device to be passed through the corresponding apertures 5, 6, or 7 of the belt. The 80 ratchet teeth and ratchet pin co-operate in a manner to permit the two members of the adjusting device to be easily pushed inward, to bring the two heads 10 and 13 toward each other, in order to decrease the distance between the end portions of the belt, but to 85 prevent the separation of the two members of the device after the same have been once adjusted.

In operation, it will be seen that the adjusting device can be pulled apart a sufficient distance so that the end portions of the belt will run straight from the body to the hooks 1 and 2, and the maximum severity of action afforded by the machine will result. Then, by simply pressing the two heads 10 and 13 toward each other, the ratchet pin will pass over the ratchet teeth 16 and the two end portions of the belt will be drawn at greater or less distance toward each other and will be maintained in this position by the engagement of the ratchet pin with the ratchet teeth. This, as stated, decreases the severity of the action, and further adjustments can be made either to further decrease the severity of the action or to increase the same, as will be 105 understood.

We claim:

1. In massaging machines of the vibrating belt type, in combination with the exercising belt, means carried by and connected therewith for adjusting opposite side portions of the belt between the body and the ends connected to the machine toward and from each other to vary the intensity of action of the belt on the body.

2. In massaging machines of the vibrating belt type, in combination with the exercising belt, flexible means connected therewith for drawing opposite side portions of the belt between the body and the ends connected to the machine toward each other to lessen the severity of action of the belt on the body.

3. In massaging machines of the vibrating belt type, in combination with the exercising belt, means for adjusting the distance be-

tween opposite side portions of the belt between the body and the ends connected to the machine to vary the intensity of the action of said belt upon the body.

5. 4. In massaging machines of the vibrating belt type, in combination with the exercising belt, adjustable means mounted thereon for varying the distance between opposite side portions of the belt between the body and the 10 ends connected to the machine to regulate the degree of action of the belt on the body.

5. An exercising belt for massaging machines of the vibrating belt type provided at each of its ends with means for attaching 15 the belt to the vibratory members of a machine and having correspondingly positioned apertures at points thereon removed from its ends for receiving a connecting means extending between the end portions of the belt 20 at such points, to hold such portions of the belt drawn toward each other, whereby the intensity of the vibrating action of the belt may be modified.

6. An exercising belt for massaging machines of the vibrating belt type provided at 25 each of its ends with means for attaching the belt to the vibratory members of a machine and having a series of correspondingly positioned apertures at points thereon removed 30 from each of its ends whereby a connecting medium may be extended between the end portions of the belt and secured in one or the other sets of apertures to hold the end portions of the belt at such selected points 35 drawn toward each other to adjustably modify the vibrating action of the belt.

7. In massaging machines of the vibrating belt type, an exercising belt having correspondingly positioned apertures at points 40 thereon removed from its ends, and adjustable means engaging in said apertures and extending between opposite side portions for varying the distance between the same to regulate the degree of the agitating effect of 45 the belt upon the body of the user.

8. In massaging machines of the vibrating belt type, an exercising belt having correspondingly positioned apertures in its end portions, flexible connecting means passed 50 through said apertures and extending between the end portions of the belt, and means for adjusting the length of said connecting means to vary the distance between the end portions of said belt, whereby to regulate the 55 degree of the agitating effect upon the body of the user.

9. An exercising belt having located at corresponding positions at points thereon removed from its ends, attaching means for 60 the ends of a connection extending between said end portions.

In testimony whereof, we have hereunto set our hands.

ALFRED D. LUEHRMANN.
FRANCIS X. MEEHAN.
